UNITED STATES PATENT OFFICE.

ELI BROTHERS, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING MACHINE.

Application filed January 23, 1917, Serial No. 144,044. Renewed December 26, 1922.

To all whom it may concern:

Be it known that I, ELI BROTHERS, a citizen of the United States, residing at Lynn, in the county of Essex and State of Massachusetts, have invented certain Improvements in Lasting Machines, of which the following description, in connection with the accompanying drawings, is a specification, like reference characters on the drawings indicating like parts in the several figures.

This invention relates to lasting machines, and more particularly to machines for use in lasting the ends of boots and shoes. The invention is herein shown as embodied in a machine particularly adapted for toe lasting, but it will be understood that the invention in many of its aspects is not limited to this particular use.

A feature of the invention consists in a novel organization of shoe positioning means and upper gripping means together with power-driven mechanism for effecting relative movements of the different parts to pull the upper and to work it into lasted position round the end of the shoe. The construction shown comprises co-operating jaws which are curved to grip the upper on a substantially continuous line round the end of the shoe, and which serve in the course of the power-effected cycle of operations of the machine to work the upper into lasted position over the feather of the sole or insole. In the illustrative machine, moreover, the shoe positioning and upper gripping means and the power-operating mechanism are so constructed and arranged that the shoe is presented with the top of the forepart in full view of the operator in his normal working position, thus enabling the operator to observe carefully the parts of the upper directly affected by the stretching action of the gripping and lasting devices without assuming any unnatural or strained position, and another feature consists in the novel organization thus provided.

Further features of the invention are to be recognized in novel means for imparting operative movements lengthwise and laterally of a shoe to upper gripping and lasting jaws, novel mechanism affording provision for preliminary adjustment of lasting members relatively to a shoe, a novel arrangement whereby different shoes may be pre-

sented properly for lasting, and in various details of construction and combinations of parts, which will now be described with reference to the accompanying drawings and pointed out in the claims.

In the drawings:

Figure 1 is a side elevation of a machine in which the invention is embodied.

Fig. 2 is a plan view.

Fig. 3 is a horizontal section on the line 3—3 of Fig. 1.

Figs. 4, 5 and 6 show successive steps in the relative movement of the last and the lasting devices.

Fig. 7 is a diagrammatic view indicating the approximate relation of the several cam paths to one another.

The machine shown is arranged to be adjustably mounted on a post with the shoe and the lasting devices at such an elevation that the operator, standing in front of the machine, shall look downwardly and forwardly over the shoe from the heel end toward the toe at such an angle that he can watch the work on the toe of the shoe and be aware at all times of the effect being produced by the lasting devices upon the upper as to smoothness of fitting over the toe portion of the last and as to the result of the stretching action upon the surface finish of the leather.

The head 2 of the machine is a hollow casting from one lateral end of which projects a boss in which is a bearing for a driving pulley 4. This pulley is connected by a friction clutch and speed reducing gears to a cam shaft 5 carrying cam blocks containing the various cams, *a*, *b*, *c*, and *d*, see Figs. 2 and 7, from which are obtained the required relative movements of the lasting devices and the last.

The lasting devices comprise essentially the upper and lower jaws 10, 12 the front edge faces of which are contoured to embrace the toe portion of a shoe, said jaws having on their opposed sides serrated gripping faces at said front edges. Each of the jaws 10 and 12 is mounted to have movement in an arc for closing and opening about and under the toe of a shoe. The two jaws 10, see Fig. 2, are secured by wing nuts 24 to studs 25 mounted in arc-shaped guideways formed in a raised boss 14 on a slide 15 movable forwardly and backwardly in

guideways in the machine head through connections with a cam roll standing in cam path *c*. These jaws are moved along said arc-shaped guideways by connections 5 through links 16 between the foremost studs 25 and the operating head 18 of a plunger 20 carrying a cam roll standing in the cam path *b*. The connections between the links 16 and the head 18 are made readily adjustable by spring locking bolts 22 and eccentric slots 23 in the head that enable the operator to fit the jaws 10 to the last over which a shoe is to be made.

The lower jaws 12 have depending flanged 15 portions which are mounted in arc-shaped guideways 26 in a slide 27 for movement in paths similar to the paths of the jaws 10, the slide 27 being movable lengthwise of the shoe on the top of a vertically movable post 20 30. The studs 25 are extended downwardly and form pivotal connection with the jaws 12 whereby said jaws 12 are advanced and retracted in their guideways 26 simultaneously, and are moved bodily lengthwise of 25 the shoe with the jaws 10.

The jaws 10 are vertically stationary. The jaws 12 are movable toward the jaws 10 for gripping the margin of the toe portion of the shoe upper and away therefrom 30 for releasing the upper. This movement is obtained by mounting the jaws 12, as above explained, upon the post 30 the stem of which is guided in a bracket 32 and which is connected to a rocking lever 35 receiving 35 motion through a link 36 from a cam roll standing in the cam path *d*. The lever 35 is mounted on a fulcrum stud carried in a fulcrum block 40 which is mounted in the head 2 for adjustment lengthwise of the 40 lever by means of a screw rod 42. This adjustable fulcrumming of the lever 35 provides for accurately adapting the jaw closing movement to the heavy or light uppers to be operated upon.

45 The shoe is carried by a support that comprises a toe rest 50, a ball rest 52 and a heel face abutment 54 the shoe engaging face of which is curved in an arc around a center located substantially at the toe of the 50 last. The rests 50 and 52 are each mounted to tip in the carrying portions of the support so that they may adjust themselves automatically to the spring or longitudinal inclination of the sole face of the shoe and 55 thereby obtain firm bearings upon the shoe. The heel abutment 54 is adjustable lengthwise of the support by a screw and hand crank 55 for adaptation to different lengths of lasts. The head of the shoe support, 60 upon which the rests and the heel abutment are carried, is adjustable in an arc-shaped guideway 56 on the head of the post 58, the adjustment being about a center located substantially at the toe of the last. This adjustment is effected by a rack 59 and seg-

ment 60 capable of operation by a hand lever having an adjustment retaining lock as shown in Fig. 1. The head of the shoe support, and therefore the shoe, is also adjustable about a vertical axis lying in the post 58 and located at or near the center of curvature of the toe of the last. The described construction permits adjustment of right and left lasts to present their toes symmetrically to the jaws 10, 12 and also adjustment to present the plane of the toe portion of the shoe bottom parallel with the plane of closing movement of the jaws 10.

70 The shoe supporting post 58 is vertically guided in a bracket projecting from the machine frame and is vertically adjustable with relation to the front end of a bell crank lever 65 the upper arm of which is provided with a cam roll through which movements are derived from the cam *a*. This vertical adjustment may be effected through rotation of a hand wheel 581 having a threaded hub engaging the post 58 the wheel and hub being held against vertical movement by an attached depending finger 582 having a lateral flange extending under an annular rib formed on a boss 583 on the upper end of the sleeve 651 which is connected to the end of bell crank lever 65 (see Fig. 1).

75 The machine is so constructed, arranged and organized that the following operation thereof may be obtained: A shoe comprising a last to which an innersole has been secured and upon which an upper has been assembled is positioned upon the rests 50, 52 with the toe end of the last abutted against the front edge face of the lower jaws 12 as shown by dotted lines in Fig. 1. The toe is centered in the machine by the curvature of the jaws 12, and the operator will position the heel end of the shoe laterally, according as it is a right or a left last, to present the forepart of the last symmetrically to the jaws. The heel abutment 80 may then be adjusted for the length of shoe to be operated upon. With the work thus presented the marginal portion of the upper, if allowed to flare outwardly in the normal position which it assumes when assembled on the last, will extend between the toothed gripping faces of the upper and lower jaws 10 and 12 as indicated in Fig. 1.

85 If the clutch now be closed to cause the driving pulley 4 to turn the cam shaft, the following movements will occur in substantially the sequence recited. The lower jaws 12 will be elevated by motion transmitted through lever 35 and will grip the margin of the upper against the lower face of the jaws 10. The shoe support will be elevated through the rocking of bell crank lever 65, thereby raising the last with relation to the gripped margin of the upper to a predetermined position which, assuming correct adjustment of post 58, will locate the tread 90

face of the shoe bottom in a plane slightly above the plane of the top face of the jaws 10. During the last part of this upward movement of the last the jaws 10 and 12 5 will be closed around the shoe by movement transmitted through the plunger 20 and simultaneously will be advanced toward the shoe by the forward movement of slide 15 effected by its operating cam, the jaws thus 10 acting as wipers to last the margin of the upper inward over the insole. The results of these combined movements are indicated in Figs. 4 and 5. In Fig. 4 the arrows indicate the simultaneous elevation of the last 15 and closing of the wipers. This results in the wrapping of the tensioned upper around the edge of the shoe bottom while the tension is being maintained or increased so that no opportunity is afforded for wrinkles 20 to form in the upper. As the jaws 10 pass under the edge of the shoe bottom toward the position shown in Fig. 5, the shoe support may descend a trifle to permit the upper to be pressed against the lower face of 25 the feather of the shoe insole. In the final position of the jaws, as shown in Fig. 5, the upper is pressed firmly into the angle between the feather and the rib of the insole with a portion upstanding from the 30 plane of the shoe bottom as a sole attaching flange held against the insole rib by the inner flange-forming edge face of the upper jaws 10.

The machine may be allowed or caused to 35 come to rest with the parts and the work in the condition just described, affording opportunity for the workman to apply a toe binder around the toe for securing the upper in lasted position. Alternatively this machine may be employed in the manufacture 40 of shoes which include toe stiffeners of the type which are pliable and adhesive when heated and which, when allowed to cool, become stiff and more or less resilient. 45 Such toe stiffening material when incorporated in a shoe responds to the shaping operation incident to the toe lasting and adheres firmly to the upper and lining materials of the shoe. When it cools it cements 50 the upper and lining together and stiffens to maintain the upper in its stretched and formed condition around the toe of the last and upon the feather of the innersole in position for sewing. The stiffening of this 55 material requires, according to its composition, one or two minutes more or less and I contemplate that by employing two lasting machines for a workman one of which may be adjusted for rights and the other for lefts, a shoe allowed to set with the parts in the 60 position indicated in Fig. 5 while another shoe is being lasted in the companion machine will be so permanently set in its lasted position that no toe fastenings will be required. 65

When the machine is restarted the lower jaws 12 will descend and the other parts will return to their starting positions, thereby freeing the shoe and allowing the operator to lift it from the shoe support. The portion of the upper materials that was located 70 between the gripping faces of the jaws may now be trimmed off and thereby leave the shoe in desirable condition for the welt sewing on operation.

Having explained the nature of this invention and described a preferred construction embodying the same, I claim as new and desire to secure by Letters Patent of the United States:—

1. In a machine of the class described, the combination of co-operating pairs of jaws shaped and arranged to embrace the toe portion of a shoe; a shoe support; and power driven mechanism connected with said jaws and said support for operating the same in time relation to grip the margin of the upper on a substantially continuous line extending around the toe from one side thereof to the other; relatively to move the jaws and the shoe support substantially perpendicularly to the plane of the shoe bottom to effect stretching of the upper over the toe of the last, and then to close the jaws inward and relatively to move the jaws and the last to cause the upper to be wrapped around the edge of the last bottom and formed upon the tread face of the inner-sole inside the edge of the last bottom in position to be fastened upon the tread face of the inner-sole. 100

2. In a machine of the class described, the combination with pairs of toe embracing jaws mounted for relative approaching and receding movements in curved paths, of an operating plunger having a head, and links connected at one end to said jaws and at the other end having connections with said head which permit the links to be adjusted on the head to vary the starting positions of the jaws. 105

3. A machine of the class described having, in combination, upper and lower toe embracing jaws and shoe supporting means relatively arranged to permit the shoe to be positioned with its toe end against the front edge of the lower jaws and to be centered relatively to the jaws by engagement with the lower jaws, and means for relatively operating the jaws and the shoe support to effect gripping and pulling of the upper. 110

4. In a machine of the class described, the combination with curved toe embracing members adapted to determine the lateral position of a shoe toe; of shoe supporting means comprising a toe rest, a ball rest, and a heel end face abutment the work engaging face of which is curved about a center located in the forepart of the last; and means for relatively operating said members 115 120 125 130

and the shoe support for lasting the toe of the shoe.

5. A machine of the class described having, in combination, toe embracing members, a forepart support comprising toe and ball rests, and means for adjusting said rests about an axis extending transversely of the last and located near the toe end of the tread face of the last.

10. 6. A machine of the class described having, in combination, upper and lower pairs of toe embracing jaws, means for relatively moving the jaws substantially perpendicularly to the plane of the last bottom to grip the upper, arc-shaped guideways in which said jaws are mounted, slides in which the guideways are formed, and means for moving said upper and lower jaws together in the guideways and for moving the slide to effect closing and advancing of the jaws to carry the upper over the tread face of the shoe bottom after the upper has been pulled.

7. A machine of the class described having, in combination, a last and shoe support, co-operating jaws curved to embrace an end of a shoe and arranged to grip the margin of the upper between them on a substantially continuous line round the end of the shoe, said jaws being mounted for inward movement over the shoe constructed to work the upper into lasted position on the feather of the sole or insole, connections between the opposed gripping jaws movable with said jaws and constraining them to move inwardly in unison laterally of the shoe, a power shaft, and operating mechanism driven by said power shaft for effecting relative movement of said support and jaws to stretch the upper and for moving the jaws inwardly together to work the upper into lasted position.

8. A machine of the class described having, in combination, a last and shoe support constructed and arranged to position a shoe bottom downward with the top of the forepart in full view of the operator in his normal working position, co-operating jaws curved to embrace an end of the shoe and arranged to grip the margin of the upper between them, said jaws being mounted for inward movement over the shoe and constructed to work the upper into lasted position on the feather of the sole or insole, a power shaft, mechanism driven by said shaft for effecting relative movement of said support and jaws to stretch the upper, and connections between said shaft and jaws for moving the jaws inwardly to work the upper into lasted position.

60. 9. A machine of the class described having, in combination, a last and shoe support constructed and arranged to position a shoe with the top of the forepart in full view of the operator in his normal working position, co-operating jaws curved to embrace an end

of the shoe and arranged to grip the margin of the upper between them on a substantially continuous line round the end of the shoe, said jaws being mounted for inward movement over the shoe and constructed to work the upper into lasted position on the feather of the sole or insole, a power shaft, and connections between said shaft and the shoe support and gripping jaws for closing the jaws on the upper, for moving the shoe relatively to the jaws to stretch the upper, and for moving the jaws inwardly to work the upper into lasted position.

10. A machine of the class described having, in combination, a last and shoe support, two pairs of curved end-embracing jaws relatively movable substantially perpendicularly to the plane of the bottom of a supported last to grip between them the edge of the upper at one end of a shoe on the last and arranged for preliminary angular adjustment substantially to conform to the contour of said end of the last, said jaws presenting a flange forming inner edge surface to the upper, and power operated means for effecting relative movement of said support and gripping jaws to form the upper to the end of the last and over the edge of the sole on the last bottom with the upper presenting a flange portion upstanding from the bottom of the sole.

11. A machine of the class described having, in combination, means to support a shoe form in position to permit the operator to look downwardly and forwardly on the top of the forepart of the shoe, two pairs of curved jaws shaped to embrace one end of the form and arranged for relative movement substantially perpendicularly to the plane of the bottom of said form to grip between them the edge of one end of a shoe upper on said form, and power operated means for effecting relative movement of said shoe form and said gripping jaws to shape the shoe upper to one end of said form and over the edge of the bottom of said form.

12. A machine of the class described having, in combination, means to support a shoe form bottom downward with its toe pointing rearwardly away from the operator, two pairs of curved jaws shaped to embrace one end of the form and arranged for relative movement substantially perpendicularly to the plane of the bottom of said form to grip between them the outspread edge of one end of a shoe upper on said form, said jaws being constructed to present a flange-forming inner edge surface to the upper, and means for effecting relative movement of said gripping jaws and the shoe form to shape the shoe upper to one end of said form and over the edge of the bottom of said form, with the shaped upper presenting a portion upstanding from said bottom.

13. A machine of the class described having, in combination, means for positioning a shoe bottom downward with its toe end pointing rearwardly away from the operator, means for gripping the upper on a substantially continuous line extending round the toe end of the shoe and along the opposite sides of the toe portion, and power-operated mechanism for effecting relative movement of said shoe positioning means and gripping means to pull the upper and to work it into lasted position under the edge of the sole or insole. 50

14. A machine of the class described having, in combination, means for positioning a shoe bottom downward with its toe end pointing rearwardly away from the operator, grippers constructed and arranged to engage the upper on a substantially continuous line round the toe and along the opposite sides of the toe portion, said grippers being constructed also to serve as end lasting wipers, and power-operated means for effecting relative movement of said grippers 60 and the shoe positioning means to pull the upper and to wipe it into lasted position round the toe. 65

15. A machine of the class described, having in combination, means for positioning a shoe bottom downward with its toe end pointing rearwardly away from the operator, grippers constructed and arranged to engage the upper on a substantially continuous line round the toe and along the opposite sides of the toe portion, said grippers being constructed also to serve as end lasting wipers, and power operated mechanism for moving said shoe positioning means to raise the forepart of the shoe relatively to the grippers to pull the upper and for moving said grippers inwardly under the shoe bottom to wipe the upper into lasted position. 70

16. In a machine of the class described, co-operating pairs of jaws curved to embrace an end of a shoe and adapted to grip and pull an upper and to work it into lasted position, said jaws being mounted for 75

bodily advancing movement lengthwise of the shoe and for relative inward movements laterally of the shoe, a power shaft, connections between the power shaft and said jaws for moving them inward laterally of the shoe, and additional connections for imparting to said jaws their bodily advancing movement. 80

17. In a machine of the class described, co-operating pairs of jaws curved to embrace an end of a shoe and adapted to grip and pull an upper and to work it into lasted position, supporting means for said jaws movable to carry them lengthwise of the shoe and upon which the jaws are guided for relative inward movements laterally of the shoe, a power shaft, connections between said shaft and supporting means for moving said means and the jaws lengthwise of the shoe, and additional connections between the power shaft and said jaws for moving them inward laterally of the shoe in time relation to their advancing movement. 85

18. In a machine of the class described, the combination with shoe positioning means, of a pair of end embracing lasting members mounted for relative closing and opening movements laterally of the shoe, an operating member, and links connecting the operating member to said lasting members, said links being adjustable on the operating member for varying the starting positions 90 of the different lasting members. 95

19. In a machine of the class described, the combination with shoe positioning means, of a pair of end embracing lasting members mounted for relative closing and opening movements laterally of the shoe, an operating member, and links connecting the operating member to said lasting members, the operating member having guideways along which said links are adjustable laterally, each independently of the other, to effect a preliminary adjustment of each lasting member independently. 100

In testimony whereof I have signed my name to this specification.

ELI BROTHERS.
